UNITED STATES PATENT OFFICE

URBAN C. THIES, OF DAYTON, OHIO, ASSIGNOR TO THE GLOBE WERNICKE COMPANY,
OF CINCINNATI, OHIO, A CORPORATION OF OHIO

HINGED STRUCTURE

Application filed December 12, 1929. Serial No. 413,532.

This invention relates to the construction of hinged members such as doors and the like.

One of the objects of the invention is the provision of a filler member of simple construction for cooperation with a hinge to provide a finished appearance at the point of hinge attachment.

Another object of the invention is the provision of a filler member for door hinges and the like which is inexpensive to produce and which may be readily mounted in reversed positions.

Other objects and advantages of the invention will be apparent from the following description, the appended claims, and the accompanying drawings.

In the drawings, which disclose a preferred embodiment of the invention—

Fig. 1 is a fragmentary elevational view of a hinged structure constructed in accordance with this invention;

Fig. 2 is a sectional view on the line 2—2 of Fig. 1;

Fig. 3 is a sectional view on the line 3—3 of Fig. 1; and

Fig. 4 is a detail of a hinge filler member.

In its illustrated form the invention is applied to a hinged member 10 shown in the form of a sheet metal door such as is used in hotels, offices and factories. In such constructions the parts used should be readily assembled and dismantled with a minimum of labor and loss of material. The component parts of the structure are generally made so that they may be used in a variety of combinations, and are usually made interchangeable so that a variety of structures may be fabricated from a minimum stock of parts. The doors, for example, are preferably provided with reversible hinges so that they may be hung from either side of the door frame to swing in either direction.

This invention discloses a manner of door construction which permits such usage and which, in addition, provides neat appearance for a door which may be quickly mounted in any desired position.

On the door 10 is a hinge 11 attached thereto by some suitable means, such as the attaching screws 13. As shown, the hinge is at-

tached to the edge 15 of the door and received in an indented or cut away depression, as at 16, so that the plate portion 17 of the hinge will lie flush with the door edge 15. In the sheet metal door shown the stile surface is cut away and a backing plate 18 is provided for the attachment of the hinge; the backing plate being preferably a metal member of rigid form, provided with extending ends 19 which may be attached to the door edge in some suitable manner such as by welding. The backing plate 18 is provided with symmetrically positioned attaching means for the hinge such as the tapped holes 20 which match the hinge plate attaching screw holes 21 so that the hinge 11 may be attached in reverse manner to enable the door to be hung for either right hand or left hand operation without inversion of the door itself.

The cut away portion 16 extends across the full width of the door stile so that the hinge plate may be attached with the hinge pin on either side. When standard hinges are used it becomes necessary to supply a filler member to take up the space between the end 70 22 of the hinge and the surface 23 of the door opposite the hinge pin 24 as the hinge plates are generally provided in a single standard width which is not long enough to extend fully across the thickness of the 75 door. Such a filler piece is provided in the member 25 which may be made as a casting although it is preferably constructed from sheet metal, as shown. The illustrated form of filler member comprises a plate portion 26 having holes 27 therethrough to permit passage of the hinge attaching screws 13, and having a formed filler portion such as the upturned end portion 28 to which is attached a flange extension 29. The plate portion 26 is preferably positioned between the door and the hinge plate 17, being shown positioned against the outer face of the backing plate 18. It is preferably held securely in position by means of the hinge and the 80 attaching screws 13. The end portion 28 is so positioned with relation to the hinge attaching hole positions that when the member 25 is held in clamped position the upturned portion 28 will lie flush with the sur- 85 90 95 100

face 23 of the door. The holes 27 in the plate 26 are preferably elongated laterally to permit exact registration of the outer surfaces of the filler piece and the door face 5 even though there may be slight errors in the hole positions in the various parts. The portion 28 is equal in length to the depth of the depression 16 and fills the end thereof to provide an unbroken surface for the side of the door opposite the hinge pin. The extending flange 29 is turned inwardly to lie flush with the surface 15 of the door, abutting and lying flush with the outer side of the hinge plate to give a neat and finished appearance. The 10 space adjacent the hinge end 22 if left exposed would present an ugly unfinished appearance upon opening the door and this is effectively corrected by the filler member 25 whose flange extension 29 may be provided 15 in a variety of lengths to accommodate doors of varying widths.

The hinge attaching holes 20 in the backing plate 18 are symmetrically arranged with respect to opposite sides of the door 10, and 20 may be provided in pairs, as shown, to cooperate with a single row of holes in the hinge plate. The holes in the filler plate 16 are arranged to correspond with the hole positions in the hinge plate. The hinge 11 may 25 be changed from left hand to right hand opening by a mere reversal of the hinge plate 17. The openings 27 in the filler member 25 being coordinated with the attaching holes in the hinge plate 17, the filler member 25 is also adapted for use on either side of the door by simply reversing the member 25 upon reversal of the hinge plate.

While the form of apparatus herein described constitutes a preferred embodiment 40 of the invention, it is to be understood that the invention is not limited to this precise form of apparatus, and that changes may be made therein without departing from the scope of the invention which is defined in the 45 appended claims.

What is claimed is:

1. In a construction of the character described, a hinged door, a reversible hinge attached to an edge of the door and terminating 50 short of the door face, said door having an edge wall provided with a depression extending from one side to the other for receiving said hinge, and a separate reversible filler member detachably mounted adjacent said hinge and filling the space between the end of the hinge and the face of the door.

2. In a construction of the character described, a hinged member, a hinge therefor, and a separate detachable filler member having 60 an attaching portion positioned between said hinged member and hinge and having one surface lying flush with the face of the hinged member and having another surface lying flush with the side of said hinge.

3. In a construction of the character de-

scribed, a hinged member, a hinge therefor, a separate removable filler member positioned adjacent the hinge and having one surface flush with the side of said hinged member and an adjacent surface flush with a side of 70 said hinge, said filler member having a length substantially equal to the length of the hinge, and means for reversibly attaching said hinge and said filler member to said hinged member.

4. In a construction of the character described, a hinged member, a hinge therefor, a filler member having an attaching portion positioned between said hinged member and hinge and having an end portion lying flush with the face of the hinged member, and fastening screws for said hinge, said attaching portion having openings for accommodating said screws in various positions of adjustment of the filler member.

5. In a construction of the character described, a door, a reversible hinge therefor extending from one side of the door almost to the other side thereof, and a sheet metal filler member, said filler member comprising a plate portion and a bent up end portion, said end portion being adapted to fill the space between the end of the hinge and the face of the door.

6. In a construction of the character described, a door, a hinge therefor, a filler member positioned adjacent said hinge and comprising a plate portion which is held in place by the hinge, an upturned end portion positioned flush with the face of the door, 100 and a flange extension flush with the outer side of the hinge.

7. In a construction of the character described, a door, a reversible hinge therefor, a separate removable filler member positioned between said door and said hinge, and means for reversely attaching said hinge to said door so the door may open to either side, said filler member having openings therethrough for the passage of said attaching means and having an end portion lying flush with the outer side of the hinge and a door face.

8. In a construction of the character described, a door, a hinge therefor, a sheet metal filler member comprising a plate portion adapted to be held between the door and the hinge, an upturned end portion extending flush with the door surface, and a flange portion extending between the end portion and the end of the hinge, said flange portion being positioned flush with the face of the door and abutting the end of the hinge.

9. In combination, a door, a hinge therefor, said door having an edge wall provided with a depression extending from one side to the other of the door edge for receiving said hinge, and a separate detachable filler member filling the space within the depre-

sion between the end of the hinge and the face of the door.

10. In combination, a sheet metal door, a reversible hinge therefor, said door being provided with a depression in the door edge for receiving said hinge, an attaching member for said hinge positioned within said door and secured thereto, means for attaching said hinge to said attaching member, a 10 filler member having a surface lying flush with a side of the hinge and having a surface lying flush with the door face, and means for removably securing said filler member adjacent said hinge.
- 15 11. A sheet metal filler member of the character described, comprising a plate portion having a series of attaching holes, an upturned end portion adapted to lie flush with a side of a door, and an inturned flange 20 tension on said portion adapted to abut and lie flush with a door hinge.

In testimony whereof I hereto affix my signature.

CERTIFICATE OF CORRECTION.

Patent No. 1,860,438.

May 31, 1932.

URBAN C. THIES.

It is hereby certified that the name of the assignee in the above numbered patent was erroneously described and specified as "The Globe Wernicke Company" whereas said name should have been described and specified as The Globe-Wernicke Company, as shown by the records of assignment in this office; and that the said Letters Patent should be read with this correction therein that the same may conform to the record of the case in the Patent Office.

Signed and sealed this 30th day of August, A. D. 1932.

**M. J. Moore,
Acting Commissioner of Patents.**
